UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A BRUSH OR MIRROR BACK.

SPECIFICATION forming part of Design No. 22,175, dated January 31, 1893.

Application filed January 3, 1893. Serial No. 457,145. Term of patent 3½ years.

To all whom it may concern:

Be it known that I, HENRY BERRY, a citizen of the United States, residing at Shelton, in the county of Fairfield and State of Connecticut, have invented and produced a new and original Design for a Back for Mirrors, Brushes, and other Articles, of which the following is a specification, reference being had to the accompanying drawing, forming part thereof, and showing a face view of a mirror or brush back bearing my design.

The leading features of my design consist in the shape of the back and the surface ornamentation thereon, as represented in the drawing.

In the drawing A indicates the mirror or brush back, and B the handle at one end thereof. The back A is somewhat rectangular in outline, and is a little wider across its upper portion than across its lower portion. The upper end of the back A is concave at the center of its edge and has rounded corners meeting the opposite side edges of the back, which side edges curve gracefully downward to the lower corners of the back and meet the curved side edges of the handle B,

whose lower end has rounded corners and is slightly concave at its center to harmonize with the outline of the upper end of the back A. Upon the upper field of the back A are the corresponding conventionalized foliate scrolls C, D, curving toward each other at their upper and lower ends, and joining at their lower ends the ornamental scroll figures E, F, which curve outward and downward to the opposite edges of the back. Below the scroll E are the border scrolls G, H, and below the scroll F are the border scrolls I, J, while centrally displayed at the lower end of the back is the conventionalized foliate base figure K. The handle B bears the ornate base scroll L and upwardly extending side scrolls M.

What I claim, is:

The design for a back for mirrors, brushes and other articles, substantially as shown and described.

Signed at Shelton, in the State of Connecticut, this 22d day of December, A. D. 1892.

HENRY BERRY.
